ROTARY JAR AND SAFETY JOINT

James G. Richey, Alhambra, Calif.

Application September 1, 1942, Serial No. 456,876

2 Claims. (Cl. 255—27)

My invention relates generally to oil well tools and appliances, and, more particularly, to a combined jar and safety joint, and my present invention is an improvement on the oil and tool vibrator patented by me November 3, 1931, Patent Number 1,829,758, and the combined safety joint and jar, forming the subject matter of my co-pending application for United States Letters Patent filed November 22, 1939, Serial Number 305,636 and which resulted in Patent No. 2,326,394, issued August 10, 1943.

The principal objects of my present invention are to generally improve upon the construction of oil well tool vibrators or jars disclosed in my aforesaid patent and patent application, as well as other existing forms of similar tools, by providing same with simple and efficient means which functions as an added safety joint to prevent the sleeve or bowl portion of the tool from un-screwing from the threaded mandrel as the result of the weight of said sleeve, and the tool carried thereby, when the drill string and tool are elevated so as to withdraw the tool from the well hole.

It will be understood that in my improved jar or vibrator a mandrel, which is connected to the lower end of the drill string and the mandrel in closing sleeve or bowl which carries the drill or other tool, are provided with interrupted threads which cooperate as the drill string is rotated to impart jarring blows to the tool in the event that the same becomes "stuck" or lodged in the formation at the lower end of the well hole and which jarring action is generally effective in loosening the drill or other implement so that the same may continue to perform its intended functions.

It sometimes happens that in pulling the drill string from the well hole, the threads on the tool carrying sleeve run off the threads on the mandrel which action is due to the weight of the sleeve and tool carried thereby while the drill string is being elevated in the hole, and it is one of the objects of my invention to provide a safety joint connection including lugs on the mandrel which engage in grooves and pockets in the sleeve for effectually preventing the sleeve from running off the mandrel.

With the foregoing and other objects in view, my invention consists in certain novel features of construction and arrangement of parts which will be hereinafter more fully described and claimed and illustrated in the accompanying drawing, in which

Fig. 1 is a vertical section taken lengthwise 55

through the center of my improved safety joint and jar and showing the tool made up for drilling.

Fig. 2 is a vertical section similar to Fig. 1, and showing the parts of the tool in position while imparting jarring vibration or jarring blows to the drill or other tool.

Fig. 3 is a fragmentary vertical section of a portion of the sleeve or bowl and showing the grooves and pockets of the safety joint therein.

Fig. 4 is a horizontal section taken on the line 4—4 of Fig. 3.

Fig. 5 is a horizontal section taken on the line 5—5 of Fig. 3.

Fig. 6 is a horizontal section taken on the line 6—6 of Fig. 3.

Fig. 7 is a fragmentary vertical section showing an over-running clutch between the sleeve and mandrel and also showing the shoulder on the mandrel for engaging the end of one of the threads on the sleeve to provide a driving connection between said sleeve and mandrel.

Fig. 8 is an enlarged horizontal section taken on the line 8—8 of Fig. 7 and looking downwardly.

Fig. 9 is a cross section taken on the line 9—9 of Fig. 2.

Fig. 10 is a cross section taken on the line 10—10 of Fig. 2.

Referring by numerals to the accompanying drawing which illustrates a preferred embodiment of my invention, 10 designates the lowermost portion of the lower member of the drill string which lower portion is internally threaded for the reception of the external threaded pin or plug portion 11, which is formed on the upper end of a mandrel 12. This mandrel is axially arranged within a sleeve comprising an upper tubular member 13, the lower end of the latter being screw seated on the upper end of a lower sleeve member 14, and the lower end of said member is internally threaded for the reception of the threaded upper end of a sub 16 to which the drill or other well tool is detachably connected.

Formed on the upper portion of the mandrel just below the threaded pin 11 is a shoulder 17, which when the tool is made up for drilling purposes, bears directly against the upper end of the upper sleeve member 13, and seated in grooves 18, that are formed in the mandrel below shoulder 17, are conventional packing rings 19 which provide a fluid pressure tight joint between the mandrel and the upper portion of upper sleeve member 13.

A short portion of the mandrel, just below the

lower groove 18, has the same external diameter as the internal diameter of sleeve member 13, thus providing a substantial bearing 20 between the upper portion of the mandrel and upper member 13 and that portion 21 of the mandrel below bearing 20 is slightly reduced in diameter with respect to the internal diameter of sleeve member 13. The lower end of this portion 21 of the mandrel terminates in a shoulder 22, which when the tool is made up for drilling purposes, rests directly on top of the lower sleeve member 14, as illustrated in Fig. 1.

A short portion 23 of the mandrel, immediately below shoulder 22, is reduced in diameter with respect to the portion 21, and the lower end of this reduced portion 23 is provided with a vertically disposed shoulder 24 that is adapted to engage the upper end of the upper one of the internal threads which are formed within lower sleeve member 14 and which engagement provides a driving connection between the mandrel and sleeve during drilling operations.

Formed in the periphery of the portion 23 of the mandrel is a series of pockets 25, the bottom surfaces of which are correspondingly inclined circumferentially and arranged to roll lengthwise of these pockets, are balls 26, which are normally pressed toward the shallow portions of the pockets by expansive coil springs 27, thus providing a conventional over-running brake or clutch between the intermediate portion of the mandrel and the upper portion of lower sleeve member 14, and which brake is effective in locking the mandrel and sleeve to each other while the tool is made up for drilling purposes, and while being raised and lowered in the well hole. This overrunning clutch is fully described and claimed in my co-pending application, Serial Number 305,636.

That portion of the mandrel below the portion 23, and which is designated by the numeral 28, is reduced in diameter with respect to the portion 23, and said reduced lower portion extends downward through the lower sleeve portion 14 and into the upper portion of the sub 16.

Extending axially through the mandrel is a bore 29 which enables fluid to be circulated through the tool and to provide a fluid pressure tight joint between the lower portion of the mandrel and the lower sleeve member 14, packing rings 30 are arranged between sleeve member 14 and the lower portion of the mandrel and which packing rings are retained in position by a nut 31.

Formed on the upper portion of the lower member 28 of the mandrel is a plurality of interrupted threads 32 which engage corresponding interrupted threads 33 that are formed within lower sleeve member 14 and the upper end of the uppermost one of these threads is adapted to engage shoulder 24 on the mandrel when the tool is made up for drilling (see Figs. 1 and 7).

Formed on mandrel portion 28, below the threads 32 is a plurality of interrupted threads 34, which are adapted to engage corresponding internal threads 35 formed within lower sleeve member 14, and the upper one of these internal threads 35 is spaced apart a distance of one thread from the lower one of the internal threads 33. The gaps between the ends of the thread sections 32 and 34 are disposed 180 degrees apart and likewise, the gaps between thread sections 33 and 35 are disposed 180 degrees apart.

The safety joint which prevents the sleeve and tool carried thereby from running off the mandrel

while the drill string is being raised or lowered in the well hole is illustrated in Figs. 3 to 6 inclusive, and this joint includes a circumferential flange 36 which is formed on the inner surface of the wall or upper sleeve member 13 and at diametrically opposite points, portions of this flange 36 are cut away to form openings 37, see Figs. 3, 5 and 6.

Formed on the inner surface of sleeve member 13, a short distance above flange 36, is a flange 38 and at diametrically opposite points, portions of this flange 36 are removed to form openings 39. The vertical planes on which the openings 37 and 39 are formed are disposed ninety degrees apart. The lower circumferential portions of the flange 38 between the openings 39 and above the openings 37 in flange 36, are cut away slight distances inwardly from said opening 39 so as to provide arcuate pockets 40 on the undersides of said flange 38 with vertically disposed shoulders 40a at the ends of said pockets. See Fig. 3.

Formed on the lower portion of mandrel member 21 at diametrically opposite points are lugs 41 which are adapted to pass through openings 37 in flange 36 and to occupy the lower portions of the pockets 40, also the channel or space which connects the lower portions of said pockets and which extends between the flanges 36 and 38 below the openings 39.

When my improved tool is made up for drilling, or while being run into, or withdrawn from the well holes, the parts of said tool may occupy the positions as illustrated in Fig. 1 with shoulder 24 bearing against the upper end of the upper one of the internal threads 33, with the upper end of lower sleeve member 14 bearing against shoulder 22 on the mandrel with the upper end of upper sleeve member 13 bearing against shoulder 17 and with the balls 26, positioned in the shallow portions of the recesses 25, so as to provide a locking engagement between the mandrel and sleeve. Under these conditions, the threads 32 and 34 on the mandrel are positioned beneath the threads 33 and 35 on the sleeve.

No claim is made in this application to the means just described for imparting jarring movement to the tool carrying sub 16, as such means is practically the same in structure and functions, as the jarring means illustrated and described in my above identified issued patents.

Thus, in effect, the tool is practically a one piece structure, and rotary motion of the drill string will be imparted through the tool to the drill, or other tool, that is connected to the lower end of the sleeve.

In the event that the drill or tool connected to the lower end of the sleeve becomes "stuck," and it is desired to impart vibration or jar thereto, in order to effect its release, the drill string is first rotated anti-clockwise, or toward the left, a sufficient distance to break the connection between the over-running brake with the lower portion 14 of the sleeve, and the drill string to which the mandrel is connected, is now drawn upwardly a short distance, until the balls 26 of the clutch are out of engagement with the upper portion of lower sleeve member 14, thus, positioning the parts as illustrated in Fig. 2. The drill string and mandrel are now rotated clockwise, or toward the right hand, and during such rotation, the drill string is put under upward stresses so that the threads 32 and 34 on the mandrel will bear against the underfaces of the threads 33

and 35 on the sleeve, consequently drawing the mandrel down the distance equal to the pitch of the threads and when the threads on the mandrel run off the threads on the sleeve, the mandrel will be drawn upward with a sudden movement due to the upward stresses impressed upon the drill string, with the result that sharp vibration or jarring blows will be imparted to the sleeve tending to move the same upward and withdraw the drill, or other tool that is stuck in the formation.

To impart downward vibration or jar to the drill or other tool at the lower end of the string, the latter is rotated toward the left hand without upward stresses and as the co-operating threads run off each other, the weight of the entire drill string will force the mandrel downward so that the underfaces of the threads on said mandrel will strike against the upper faces of the threads on the lower sleeve member 14, thereby imparting downward blows to said sleeve and to the drill, or tool connected thereto.

In the event that the weight of the sleeve and tool carried thereby, should overcome the binding action of the over-running brake and run off the threads 33 and 35 on the mandrel while the drill string is being raised or lowered in the well hole, the sleeve after running off the threads 33 and 35 will drop until flange 36 on the bowl strikes and comes to rest upon lugs 41.

As a result of this engagement, the sleeve will be carried upward or downward with the drill string and mandrel.

Should sleeve 14 rotate so as to bring openings 37 into position above lugs 41 then said sleeve will drop and lugs 41 after passing through openings 37 will pass upward into pockets 40 and strike against the under faces of flanges 38 between shoulders 40a, thereby arresting further downward movement of the sleeve.

Should the sleeve rotate while lugs 41 are in the pockets 40, such rotation will be limited as said lugs engage the shoulders 40a at the ends of said pockets, thus preventing detachment of the sleeve from the mandrel.

Should the sleeve frictionally contact the formation around the well hole and stop momentarily while the drill string is being lowered with the lugs on the downwardly moving mandrel positioned in the pockets 40, said lugs will travel downward until they strike against the upper face of flange 36 and thus cause sleeve to travel downwardly with the mandrel and drill string.

Should jarring operations fail to release the tool which is stuck and it becomes necessary to leave same in the well hole, then drill string is manipulated so as to cause lugs 41 to pass through openings 37 into pockets 40 and the mandrel is now lowered slightly and rotated to

position notches 39 in upper flange 38, directly above the lugs 41, thereby enabling said lugs to pass through said notches 39 as the mandrel is drawn upward (see dotted lines and arrows in Fig. 3).

Thus it will be seen that I have provided an oil well tool safety joint and jar, which is of simple structure, inexpensive of manufacture and very effective in performing the functions for which it is intended.

Minor changes in the size, form and construction of the various parts of my improved safety joint and jar may be made and substituted for those herein shown and described without departing from the spirit of the invention, the scope of which is set forth in the appended claims.

I claim as my invention:

1. In a safety joint, the combination with a rotatively associated sleeve and mandrel having means for limiting relative longitudinal movement in one direction and said mandrel having a lug, of a pair of spaced internal circumferential flanges on said sleeve, a portion of the lower flange being cut away to form an opening, a portion of the upper flange being cut away to form an opening offset from the opening in the lower flange, the lower portion of the upper flange being cut away circumferentially to provide a pocket, the ends of which terminate adjacent the opening in said upper flange and the distance from the top of said pocket to top of the lower flange being substantially greater than the height of said lug.

2. In a safety joint, the combination with a rotatively associated sleeve and mandrel having means for limiting relative longitudinal movement in one direction and said mandrel having a lug, of a pair of spaced internal circumferential flanges on said sleeve, a portion of the lower flange being cut away to form an opening to permit the passage of said lug, a portion of the upper flange being cut away to form an opening for the passage of said lug, said openings being offset circumferentially relative to each other, lugs depending from the upper flange adjacent the opening therein, which lugs provide stops for limiting the movement of said lug circumferentially while in engagement with the underface of said upper flange, the distance between the underface of the flange and the upper face of the lower flange being substantially greater than the height of the lug on said mandrel and the distance between the lower faces of the lugs on said upper flange and the upper face of the lower flange, being slightly greater than the height of the lug on said mandrel.

JAMES G. RICHEY.
